CLAIM

An ornamental design for a display screen or portion thereof with graphical user interface, as shown and described.

DESCRIPTION

The single FIGURE is a front view of a display screen or a portion thereof with a graphical user interface.

The outer broken lines in the single FIGURE show the display screen or portion thereof, and form no part of the claimed design. The other broken lines in the single FIGURE show portions of the graphical user interface that form no part of the claimed design.

1 Claim, 1 Drawing Sheet
